UNITED STATES PATENT OFFICE.

CHRISTIAN D. BAIER, OF CISSNA PARK, ILLINOIS.

DROP-BOARD CLEANER FOR HENHOUSES.

Application filed May 28, 1925. Serial No. 33,354.

To all whom it may concern:

Be it known that I, CHRISTIAN D. BAIER, a citizen of the United States, a resident of Cissna Park, in the county of Iroquois and 5 State of Illinois, have invented new and useful Improvements in Drop-Board Cleaners for Henhouses, of which the following is a specification.

This invention has reference to improvements in hen house constructions and it has 10 for its principal object to improve the roost and drop board cleaners thereof.

The invention has for a further object to provide a roost hinged at its rear end to 15 adapt it to be raised at its front end and a cleaner bar movable forwardly and rearwardly along the drop board to remove the droppings thereon; means being provided to raise and lower the roost and move said 20 cleaner bar, and a common operating means being provided to operate the roost and cleaner bar operating means.

A further object of the invention is to provide a hen house with a drop board having 25 an inclined surface and a transversely disposed receiving trough at its forward end in communication with an opening or openings in the side walls of the house; a hinged roost overlying the drop board; a cleaner 30 bar movable over the surface of said board; means to raise and lower said roost; means to move said bar; and means to simultaneously raise and lower said roost and move said cleaner bar.

35 That the invention may be more fully understood, reference is had to the accompanying drawings forming a part of the description, illustrating a preferred embodiment of the invention, in which:—

40 Figure 1 is a cross-sectional view through a hen house showing my invention embodied therein, and

Figure 2 is a detail, in plan, of the operating means for the roost and cleaner bar.

45 Like characters of reference denote corresponding parts throughout the figures.

In the drawings, the hen house 1, is not unlike houses of this type having front and rear walls 2 and 2 respectively, and end walls 50 4 with a sloping roof 5. The front wall having doorways closed by doors 6.

The drop board 7 is inclined upwardly from front to rear, as shown, and extends forwardly from the rear wall 3 to a point removed some distance to the rear of the front wall 2, terminating in a transversely ar-

ranged trough 8, at its front end, communicating with an opening or openings 9 in the side wall or walls 4 of the house. The droppings cleaned from the surface of the drop board and deposited in said trough may be removed therefrom by being swept or raked from said trough through the opening or openings 9. The drop board is elevated at a height above the floor of the house and its front end removed from the front wall to provide scratching space therebeneath.

10 designates a roost, comprising longitudinal boards 11 hinged to the rear wall 3 of the house, at 12. Cross roost boards 13 connect said boards 11 and the roost provided with rests 14. Said roost is elevated at a suitable point above the drop board and inclined at the same inclination as said drop board.

15 designates a cleaner bar disposed transversely of the drop board and arranged to be moved forwardly and rearwardly thereof over its surface to scrape the latter and remove droppings thereon into the trough 8, referred to. To said bar are connected chains 16 which lie above and below the drop board 7, passing over wheels 17 journaled at the rear end of said drop board and connected to drums 18 secured to a shaft 19 disposed transversely of the drop board and at the front end thereof. Connected to said shaft is a chain 20 which passes up and over a guide wheel 21 suspended from the roof 5 and down and is connected to the front end 90 of the roost 10. And 22 is a preferably short operating shaft journaled in suitable bearings 23 secured to the front wall 2 and on said shaft is a sprocket wheel 24 which is connected by a chain 25 with a sprocket 95 wheel 26 on the shaft 19. A crank 27 is connected with one end of the shaft 22 to operate the same.

In operation, with the roost and cleaner bar in the positions shown in full lines in Figure 1, and it being desired to clean the droppings from the drop board, the operator or attendant will actuate the shaft 22 which will impart rotation to the shaft 19 moving the upper runs of the chains 16 forwardly dragging the cleaner bar 15 over the surface of the drop board and cleaning said board of droppings, which are deposited in the trough 8. Simultaneously with the forward movement of the cleaner bar, the roost is 110 elevated, as shown in dotted lines. Reversing the operation of the shaft 22 will move

the lower runs of the chains 16 forwardly dragging the cleaner bar rearwardly and permit the lowering of the roost, simultaneously into its normal rest position.

5. What I claim is:—

1. In a hen house, a drop board having a trough at its forward end, a roost hinged at its rear end to adapt it to be raised and lowered at its forward end, a cleaner bar 10 movable over the surface of said drop board beneath said roost, and means to simultaneously raise and lower said roost and to move said cleaner bar.

2. In a hen house, a drop board having a 15 trough at its forward end, a roost hinged at its rear end to adapt it to be raised and lowered at its forward end, a cleaner bar movable over the surface of said drop board beneath said roost, means to raise and lower 20 said roost, means to move said cleaner bar

forwardly and rearwardly, and a common means to simultaneously actuate said roost raising and lowering means and said cleaner bar moving means.

3. In a hen house, a drop board having a 25 trough at its forward end, a roost hinged at its rear end to adapt it to be raised and lowered at its forward end, a cleaner bar movable over the surface of said drop board beneath said roost, a shaft, a chain connected with said shaft and roost by means of which the latter is raised and lowered, chains connected with said shaft and said bar by means of which said bar is moved, an operating shaft, and operating connections between 30 said shafts.

In witness whereof I have hereunto affixed my hand and seal this 16 day of May, 1925.

CHRISTIAN D. BAIER.
